UNITED STATES PATENT OFFICE.

ROBERT ABBOTT HADFIELD, OF WESTMINSTER, ENGLAND.

APPARATUS FOR APPLYING AIR-BLAST TO INGOTS.

1,172,279.

Specification of Letters Patent.

Patented Feb. 22, 1916.

Application filed June 13, 1912. Serial No. 703,378.

To all whom it may concern:

Be it known that I, Sir ROBERT ABBOTT HADFIELD, knight, a subject of the King of Great Britain and Ireland, residing at Westminster, England, have invented Apparatus for Applying Air-Blast to Ingots, of which the following is a specification.

My invention relates to an apparatus and arrangement of plant whereby the process 10 of my United States Patent No. 933,751, may be desirably practised, and the steel in the upper part of the ingot mold may be maintained, immediately after casting, in a fluid condition for a sufficient length of time so 15 that the pipe, commonly present in ingots cast by the ordinary method, will be practically eliminated.

The ingots are preferably cast in molds placed on bogies, trucks or movable plat- 20 forms, arranged on tracks leading from the casting pit to the strippers. My invention consists in arranging over said tracks at a suitable point an air pipe, or series of air pipes, connected to a compressed air cham- 25 ber, or other suitable source of air blast. Said pipes are provided with a series of jets or holes on their under surfaces so that the air jets therefrom will impinge on the upper surfaces of the ingots. It will be understood 30 that immediately after casting, a layer of charcoal or equivalent is placed on top of each ingot, and preferably between it and the steel a layer of slag. By applying to this the air blast the freezing of the molten steel 35 is delayed so long that the pipes are eliminated, as aforesaid.

My invention will be understood by reference to the drawing herewith in which the reference numerals of the description indi- 40 cate the corresponding parts in all the figures.

Figure 1 is a plan showing the arrangement of the casting-pit, tracks and air pipes. Figs. 2 and 3 are respectively side and end 45 elevations showing the bogies and ingot molds in position under the air pipes. Fig. 4 is a vertical section of an ingot mold on the bogie, showing the air pipes in cross section. Fig. 5 is an enlarged detail view in 50 cross section of the blast pipes 11 and sleeve 16 showing the holes 14 and slots 17.

In the figures 1 indicates the casting pit, 2 the ladle on the crane 3, 4 the ingot-molds into which the molten steel has been poured,

arranged on the bogie 5. Four ingots are 55 shown here on each bogie, but more or less may be placed on each.

6 is a line of tracks for the bogie which at 7 split into three lines 8 8 8 leading to the strippers at about the point 9. Above these 60 tracks are arranged horizontally the series of blast pipes 11 extending between the cross pipes 10 10 on the upper ends of the vertical supply pipes 12, having valves 13, and leading from the air chamber. Said blast pipes 65 are at such a height that the ingot molds on the bogies will pass freely under them and the air from the holes 14 be free to impinge on the top of the hot ingot, covered by charcoal, etc. As many lines of blast pipes as 70 desirable may be provided over each track. I have shown three.

As shown in Figs. 1 and 2 the air pipes are arranged in sections, so that the blast from each section may be controlled by a 75 valve, for it is not necessary that the air should flow from the entire length of blast pipes when only a limited number of bogies are passing. For instance as shown in Fig. 2 bogies happen to be in only the right hand 80 section, so only the valve at the right is open permitting the jets to escape in that section, but the other valves are closed.

In addition the individual pipes may be fitted with sleeves 16 having perforations or 85 slots 17, or similar means, which sleeves may be rotated to control the escape of air. As however it would be found that with normal working a continuous line of bogies would be passing underneath the air pipes, 90 that is to say, there would be no break between the continuity of the bogies, the combustion which is intensified and effected by the air jets on to the charcoal would be effectively performed and carried out whether 95 the ingots on the bogies were moving or at rest owing to the continuity of the air holes or jets in the pipes which exert the pressure necessary for proper combustion of the charcoal being at whatever position the bogies 100 and the molds may happen to be, provided they are within the range of the overhead air pipes.

It will thus be seen that if the passage of the bogies from the casting pit until they 105 arrive at the stripper is relatively slow, the overhead air pipes need not be so long as in the case the passage of the bogies from the

casting pit to the stripper is at a more rapid rate, for it will be evident that in the latter case the overhead pipes would have to be of greater length than if the bogies were traveling under them at a slower rate.

Approximately the time that is necessary for the blast to operate on the upper surface of the molds, that is to say, from the time they are cast until the steel is sufficiently set 10 to avoid any danger of piping, would be in the case of rail ingots from about fifteen to fifty minutes according to the size of the ingot though this time is only stated approximately. Also, when the rate of progress is 15 known at which the ingots move from the casting pit to the stripper, that is, the time from which the ingots are cast until they can be with safety removed from their molds, the length of the overhead pipes can be easily 20 calculated.

Probably it will be preferable to use three air pipes, these pipes being arranged at such a distance from each other as will enable the three rows of jets to play upon the 25 molten steel which forms the heads of the ingots.

The height from the track to the upper side of the runner box should be approximately the same in every case so that the air 30 jets have the same heating effect on every ingot.

When the bogies arrive at the stripper, the ingot molds are lifted and the ingots removed from the molds in the usual manner, 35 preferably retaining the ingots in a vertical position during the process of stripping. Considerable modification of this arrangement can be made as may be desired. Ingots may be cast in this way with either their 40 large or small end at the bottom, or with their large or small end at the top, whichever may be preferred, or practically parallel ingots may be produced of any desired size, section, or shape.

45 This method may be also applied to the production of castings of various types.

I do not propose to limit myself to the exact form and arrangement of parts here shown for instance it is not necessary that 50 the tracks should extend straight from the casting pit to the strippers, they may be curved and the blast pipes correspondingly arranged.

As shown in Fig. 4, 20 are the trunnions 55 of the ingot mold, 21 the head of sand or other non-conducting material in the metal ring 22 having trunnions 23. The ingot is shown cast large end up but this may be reversed.

60 I claim,

1. An apparatus for supplying air blasts for producing heat to feed ingots comprising suitable supports, air conductors carried on said supports, said conductors 65 being positioned to cause impinging of the

air on the ingots during their progress to the stripper, and means for moving the ingots along under the air supply.

2. An apparatus for supplying air blasts for producing heat to feed ingots comprising suitable supports, air conductors carried by said supports, said conductors having outlets arranged in a line to permit impinging of the blasts on the ingots during transit thereunder, and means for moving the ingots along under the air blast. 70 75

3. An apparatus for causing air jets to impinge on ingots immediately after casting, comprising a track from the casting pit to the strippers for bogies carrying the 80 ingot molds, a series of vertical pipes, cross-pipes on the vertical pipes, a series of parallel, horizontal blast pipes, connected to the cross pipes and arranged over the track at such a height that the bogies and ingot molds will pass under them, said blast pipes being perforated on their under surfaces, and air valves in the vertical pipes. 85

4. An apparatus for causing air jets to impinge on the upper ends of ingots in the 90 molds immediately after casting to eliminate pipes, comprising a series of tracks from the casting pipe to the strippers, bogies or trucks on said tracks for carrying the ingot molds and the ingots therein, a 95 series of vertical air pipes arranged adjacent the tracks and connected to the source of air supply, a series of lateral air pipes arranged on the upper ends of the vertical pipes and across the tracks, air valves in the 100 vertical pipes and a series of parallel, horizontal blast pipes connected to the cross-pipes, arranged above each track and extending longitudinally of the tracks, said blast pipes being perforated on their lower surfaces and being arranged at such a height that the ingot molds on the bogies will pass beneath them but the upper ends of the ingots will be adjacent thereto said air pipes being connected in sections, that 105 the air may be cut off from each section 110 separately, substantially as described and shown.

5. An apparatus for supplying air blast to impinge on ingots immediately after 115 casting, comprising longitudinally extending air conductors so arranged as to cause the air to impinge on the ingots while the latter are being moved adjacent the conductors. 120

6. An apparatus for supplying air blasts to impinge on ingots immediately after casting, comprising longitudinally extending air conductors having longitudinal openings at one side and so arranged as to 125 permit air from the openings to impinge on the ingots while the latter are being moved adjacent the conductors.

7. An apparatus for supplying air blasts to impinge on ingots immediately after 130

casting comprising longitudinally extending elevated air conductors, provided with jets on their under surfaces to permit air therefrom to impinge on the ingots arranged below.

8. An apparatus for supplying air blasts to impinge on ingots immediately after casting, comprising suitable supports and elongated air conductors on said supports, the conductors being arranged to cause impinging of the air simultaneously on a plurality of ingots arranged below.

9. An apparatus for causing an air blast to impinge on the upper ends of ingots immediately after casting to eliminate pipes, comprising the casting pit, a series of tracks leading therefrom, trucks or bogies on the tracks, ingot molds and ingots on the trucks, means to move the trucks along the tracks and means to apply a blast to the upper ends of the ingots as they are moving.

10. An apparatus for causing air jets to impinge on the upper ends of ingots in the molds immediately after casting to eliminate pipes, comprising the casting pit and the strippers, a single track from the casting pit, said track splitting into a plurality of lines extending to the strippers, suitable supports, a plurality of series of air blast pipes carried on said supports at such a height above the tracks that the trucks with the ingots thereon will pass under the pipes, said pipes being arranged one series centered over each line of tracks, the pipes having perforations on their lower surfaces and means to supply compressed air to the pipes.

11. An apparatus for causing air jets to impinge on ingots immediately after casting, comprising suitable tracks, bogies on the tracks, ingot molds on the bogies, a series of pipes arranged over the tracks at such a height that the bogies and ingot molds will pass under them, said blast pipes being perforated on their under surfaces, and connections between the blast pipes and the source of air supply.

12. An apparatus for causing air jets to impinge on ingots immediately after casting, comprising a suitable track, bogies on the track, ingot molds on the bogies, a series of vertical air pipes, cross pipes connecting the vertical pipes, series of blast pipes connecting the cross pipes and arranged over the track at such a height that the bogies and ingot molds will pass under them, said blast pipes being perforated on their under surfaces, and air valves in the vertical pipes.

13. An apparatus for causing air jets to impinge on ingots immediately after casting, comprising casting pit, tracks therefrom, bogies on the tracks, ingot molds and

ingots on the bogies, a series of vertical air pipes, a series of blast pipes supported on the vertical pipes and connected thereto and arranged over the tracks at such a height that the bogies and ingot molds will pass under them, said blast pipes being perforated on their under surfaces, and means to open and close communication between the source of supply and the vertical pipes.

14. An apparatus for causing air jets to impinge on the upper ends of ingots in the molds immediately after casting to eliminate pipes, comprising the casting pit and the strippers, a series of tracks from the casting pit to the strippers, bogies or trucks on said tracks, ingot molds and the ingots on the bogies, a series of substantially vertical, supporting pipes arranged adjacent the tracks and connected to the source of air supply, a series of lateral air pipes arranged on the upper ends of the vertical pipes and across the tracks, air valves in the vertical pipes and a series of substantially parallel and substantially horizontal blast pipes connected to the lateral pipes, arranged above each track and extending longitudinally of the tracks, said blast pipes being perforated on their lower surfaces and ingot molds on the bogies will pass beneath them and the upper ends of the ingots will be adjacent thereto.

15. An apparatus for causing air jets to impinge on the upper ends of ingots in the molds immediately after casting to eliminate pipes comprising a single track extending from the casting pit and splitting into a plurality of lines extending to the strippers, bogies or trucks on said tracks for carrying the ingot molds and the ingots therein, a series of vertical air pipes arranged adjacent said lines of tracks and connected to the source of air supply, a series of lateral air pipes arranged on the upper ends of the vertical pipes and across the tracks, and a series of parallel, horizontal blast pipes connected to the cross-pipes, arranged above each track and parallel thereto, said blast pipes being perforated on their lower surfaces and being arranged at such a height that the ingot molds on the bogies will pass beneath them but the upper ends of the ingots will be adjacent thereto, said air pipes being connected in sections, that the air may be cut off from each section separately, substantially as described and shown.

Signed at 22 Carlton House Terrace, Westminster, England, this twenty-ninth day of May, 1912.

ROBERT ABBOTT HADFIELD.
